[57] CLAIM

The ornamental design for a wrist watch, as shown and described.

DESCRIPTION

FIG. 1 is a front elevational view of a bracelet watch showing my new design;

FIG. 2 is a left side elevational view thereof;

FIG. 3 is a fragmentary right side elevational view thereof, portions of the band being broken-away for ease of illustration;

FIG. 4 is a fragmentary rear elevational view thereof, portions of the band being broken-away for ease of illustration;

FIG. 5 is a fragmentary cross-sectional view thereof as taken from line 5—5 of FIG. 2.
